US00D800307S

(12) **United States Design Patent** (10) **Patent No.:** **US D800,307 S**
DeNeui (45) **Date of Patent:** **** Oct. 17, 2017**

(54) **TROCAR**

(71) Applicant: **BioTE Medical, LLC**, Irving, TX (US)

(72) Inventor: **Dustin C. DeNeui**, Colleyville, TX (US)

(73) Assignee: **BIOTE MEDICAL, LLC**, Irving, TX (US)

(**) Term: **15 Years**

(21) Appl. No.: **29/555,931**

(22) Filed: **Feb. 25, 2016**

(51) **LOC (10) Cl.** **24-02**

(52) **U.S. Cl.**

USPC **D24/146**

(57) **CLAIM**

The ornamental design for a trocar, as shown and described.

DESCRIPTION

FIG. 1 is a perspective view of an embodiment of a trocar of the present application;

FIG. 2 is a right side elevational view of the trocar of FIG. 1;

FIG. 3 is a left side elevational view of the trocar of FIG. 1;

FIG. 4 is a top elevational view of the trocar of FIG. 1;

FIG. 5 is a bottom elevational view of the trocar of FIG. 1;

FIG. 6 is a rear elevational view of the trocar of FIG. 1;

FIG. 7 is a front elevational view of the trocar of FIG. 1;

FIG. 8 is a perspective view of the trocar of FIG. 1;

FIG. 9 is a perspective view of an embodiment of a trocar of the present application;

FIG. 10 is a right side elevational view of the trocar of FIG. 9;

FIG. 11 is a left side elevational view of the trocar of FIG. 9;

FIG. 12 is a top elevational view of the trocar of FIG. 9;

FIG. 13 is a bottom elevational view of the trocar of FIG. 9;

FIG. 14 is a rear elevational view of the trocar of FIG. 9;

FIG. 15 is a front elevational view of the trocar of FIG. 9; and,

FIG. 16 is a perspective view of the trocar of FIG. 9.

The broken lines shown in FIGS. 1, 6-9 and 14-16 depict environmental subject matter only and form no part of the claimed design.

1 Claim, 10 Drawing Sheets
